218,290

SHOPPING BAG HANDLE OR SIMILAR ARTICLE

Saul Klarer, 4817 4th St., Laval, Quebec, Canada
Filed Apr. 19, 1968, Ser. No. 11,527

Claims priority, application Canada Nov. 10, 1967

Term of patent 3½ years

Int. Cl. D9—99

U.S. Cl. D9—292

FIG. 1 is a side elevational view of the exterior of one side of a shopping bag handle or similar article embodying the design of the present application, the other side of said handle having the same appearance as that shown;

FIG. 2 is a top plan view; and

FIG. 3 is an end view.

I claim:

The ornamental design for a shopping bag handle or similar article, as shown.
